STRATFORD B. ALLEN, OF CAMBRIDGE, MASSACHUSETTS

RESISTANCE UNIT

Application filed March 30, 1928. Serial No. 265,885.

This invention relates to improvements in resistance units and processes for their manufacture. More especially it relates to the terminal capping of tubular units.

5 The tube may for example be of glass, with a metal lying dispersed in extremely small particles over the interior surface of the tube. This provides a non-inductive resistance, which has been found particularly useful in 10 connection with radio apparatus in the range between 200 ohms and 15 million ohms, but which is also capable of being made for low resistance.

The invention provides improvements relating especially to the closing of the tube ends by metallic caps, and to the connections of the caps, interior and exterior, mechanical and electrical. It provides a method of manufacture simpler and cheaper than heretofore; and a product correspondingly less expensive. It improves the uniformity and reliability of mass production of such units; also it makes them more rugged and dependable in service. An important feature contributing to these results is the elimination of delicate operations heretofore requisite, with substantial saving in material and labor. Further it provides for the speedy making of the permanent connections when a completed unit is put into service; and provides especially for the setting of a series of units branching from a single conductor, without certain costs for preparation, installation and connection that attend the use of all other units of this nature heretofore known to me, including a considerable saving in labor costs in the industrial use of such a unit.

40 The terminal caps hitherto used are metallic cups which fit over the ends of the glass tube. The cap of the invention has a central interior mound leaving an annular groove into which the annular wall constituting the tube can be received. A relatively small quantity of hot molten sealing alloy having 45 been deposited in the groove, and the upper end of the tube being closed, temporarily or permanently, and the usual plug or stopper being omitted from the lower end of the tube, the lower end of the tube is to be thrust down 50 into the said molten alloy in the groove.

Heating and expansion of entrapped air results, and this drives some of the alloy out from the tube interior by forcing it up between the tube and the surrounding wall of the cup. The glass becomes heated from both 55 inside and outside so that the glass does not break from heat stresses. The liquid alloy behaves peculiarly. Even though it be a substance which does not wet the glass, but which when in contact therewith initially 60 and normally assumes a convex surface formation toward the glass surface, it in the circumstances stated can be made to assume a concave surface curve extending up the tube's interior, like a concave meniscus. I believe this phenomenon due to the combined effect of the said expulsion of air and of the cooling and solidification of liquid which occur where it contacts with the glass, the former continuing after the latter has begun. 70 Having solidified, this alloy provides the necessary mechanical security of position and electrical interior connection of cap with resistance. Exterioly, the cylindrical sides and protuberant terminal cone of the cap 75 adapt the unit for convenient connections according to practice heretofore; but there is added a groove crossing the axis of the protuberant cone, of proper size to receive a conductor wire and, with a bit of solder to hold it in permanent security. It is a feature that the terminal grooves at the two ends of a unit may be in a plane together, or may be arranged at angles to each other, so as to connect wires running in different directions, 85 and that this angular arrangement can be made very inexpensively.

It is intended that the patent shall cover by suitable expression in the appended claims, whatever features of patentable novelty exist 90 in the invention disclosed.

In the accompanying drawings:

Figure 1 is an elevation of a resistance unit embodying the invention, with terminal 95 grooves in the same plane;

Figure 2 is an elevation, in medial section on line 2-2 of Figure 1 on a larger scale;

Figure 3 is an elevation showing a group of the units, illustrating terminal slots in a 100

unit arranged angularly with respect to each other; and

Figure 4 is a plan of the same.

Referring to the drawings, a tube or shell 10 represented in this instance as being of glass, is to be capped at each end by metallic cups 12. Such may be inexpensively formed from solid rod stock by automatic machinery. Prior to the assembling of the unit the shell 10 will have been treated interiorly so as to constitute a conductor having the desired resistance. For this the drawings represent at 14 a thin deposit; but the substance thus deposited and the manner of its deposit constitute no part of the present invention. They may be of any sort suited to the purpose of the tube, as for example, a deposit of a metal in dispersed particles from a liquid solution, making a very high resistance; and also the 20 particular nature of the tube is immaterial, as the invention is applicable whether it be of insulating material, as illustrated, or of conducting material.

An important feature resides in the inexpensive method by which permanent electrical contact is attained between the interior high resistance surface of the shell and the end caps 12, and at the same time the caps become secured rigidly and permanently on 25 the ends of the shell. For these purposes each cap, instead of having the usual concave conical bottom left by the drill which excavated its interior, has interiorly a central mound 16 of unexcavated material between which mound and the cylindrical wall of the cap lies an annular tube-receiving valley or groove 18. When a unit is to be assembled a little molten sealing alloy 19 is placed 30 in the cup 12, which is then held with its axis vertical so that the liquid 19 distributes itself throughout the groove 18. Preferably an alloy is used having characteristics of similarity to type metals. This melts at a high temperature as compared with ordinary solder. 35 The workman, closing the upper end of the tube 10 with his finger (protected by a rubber glove), but leaving the lower end of tube open, inserts the lower end of the tube into the said groove in the cap. Air is thus entrapped in the tube between finger and cup, becomes highly heated by the molten alloy, and thus acquires expansive pressure sufficient to prevent the liquid from rising freely 40 within the tube, as the end of tube sinks into the liquid, and to cause some of the liquid alloy to be forced out between the outside wall of the tube and the closely surrounding barrel 12' of the cup, passing out through irregularities which always exist in the bottom 45 edge of the glass tube 10. Assuming that the molten alloy was not supplied to the cup in such quantity as is illustrated in the top part of Figure 2, sufficient to overflow the central mound, nor in such quantity that the insertion 50 of the tube raises its level to this extent,

that is, assuming the condition portrayed in the bottom part of Figure 2, the expulsive effect on the liquid is enhanced by the fact that the only surface which can yield to the expanding air is the surface of liquid near 55 the wall of the tube. For a given expansion of air the liquid is therefore depressed to a greater distance than if it lay across the entire bottom of the cap. As the solidification begins next to the cool body of glass and next to the cool body of the central mound, the expulsion occurs to a greater extent from the middle space of the groove. The metal which is forced out may be recovered and used again. Such as remains between the walls 60 of the tube and cup as at 20' solidifies there and assures a tight fit. That which remains within the tube lies in the bottom of the groove and has a surface 20 like a concave meniscus reaching from the interior mound 65 16 of the cup to the coated tube wall. Because of the presence of the unexcavated material 16, and because of the quasi-meniscus formation 20 the quantity of sealing alloy 70 19 consumed in making certain a good electrical and mechanical joint is far less than heretofore required to fasten a cap on a tube. Also there is less dimension of space from 75 contraction, if contraction occurs in cooling. The leaving of the end portion of the interior 80 of the tube open for the heat reaction between air and alloy, by omitting the cork plug heretofore used, both saves the cost of making and inserting the plug, and also exposes the glass to a temperature at its inner 85 face approximating that to which its outer face is subjected, thus preventing glass breakage from unequal heat stresses.

One end of the shell having been capped, the other end may be capped in like manner; and a complete, simple, substantial and efficient resistor unit results.

If it happens that more sealing alloy than necessary is run into the groove, for example, enough to cover the central mound as is represented to have happened when the end at the top of Figure 2 was sealed, the resulting product may nevertheless have the predetermined desired resistance value, approximately. Before the sealing a band of carbon may be laid over the resistance substance at each end of the shell as indicated at 22, to a width suitable to leave a predetermined length of the resistance between bands. This may be done by preliminarily dipping the coated tube end into a liquid having carbon in suspension, as a paste of ground graphite, and then letting it dry; or by otherwise painting the interior with carbon or other conductor with which the alloy will readily connect. The electrical resistance of the unit will then be substantially that of the higher resistance deposit lying between the carbon bands, and a variation in height of sealing 120 125 130

alloy will not appreciably vary the total resistance.

Exterior conical points 24 on each end cap 12 constitute the terminals of the unit 5 and are adapted to fit the ordinary spring clips (not shown) which are sometimes available for mounting such units between conical sockets; or the barrel walls 12' of the cap may be set into ordinary cylindrical 10 clamps. According to the invention, however, additional means is provided for effecting permanent connection of a unit in an electrical circuit. A groove 26, cut across the exterior of each cap in the plane of the 15 axis, is adapted to receive a wire 28 or 30 crossing the axis lengthwise of the groove, where a drop of solder will secure it quickly and permanently. An important feature is that the grooves in opposite terminals of a 20 particular unit may be arranged at any desired predetermined angle with respect to each other. Then in a series of units, indicated in Figure 3 of the drawings, a single bare wire conductor 28 may run in a straight 25 line through one terminal of every unit of the series; and the several opposite terminals, at the top of Figure 3, may be connected to individual conductors 30 extending in various directions, which is an im- 30 portant element of structure, especially in cases where it is desired to organize the units close together on a very short length of wire 35 28. The making of the desired angles of groove direction can be accomplished with precision by the setting of automatic machinery cutting the groove, if this be done after the caps have been fixed rigidly on the tube. Or, if the grooves are cut before assembly, it is only a matter of setting the cap 40 with its groove at the angle desired, when affixing the second cap. The invention makes it possible for the unit to be set up on wires 28, 30 with ordinary solder such as the public are accustomed to use. This is made possible 45 by the use of a sealing alloy 19 within, whose melting point is higher than that of ordinary wire solder, such as half lead and half tin; and this in turn is made possible by the described method which prevents the 50 glass from undergoing heat strains due to unequal application of high temperatures. The introduction of such a high melting alloy also permits of the subsequent operating of the resistance at higher load than resistances of this type heretofore made by others, 55 because the increase of temperature resulting from the higher load does not melt this alloy as it might the "Wood's metal" or like alloy heretofore commonly used for interior seal- 60 ing because its low melting point is safer for glass. The presence of the carbon band tends to prevent the alloying of the sealing 65 alloy with the metal that is in position on the interior of the tube to constitute the resistance. The composition selected for the

sealing alloy is preferably one which has as near as may be the same coefficient of expansion as the glass, in order not to shrink away from it in cooling, and in order not to break it by expansion.

The completed product disclosed has many advantages, among which are the ease and simplicity of making perfect and permanent connection of a series of the units in electrical apparatus; the small amount of 70 solder needed; the ability to use ordinary solder to ensure proper connection of external conductor in the terminal groove; and the high temperature at which the unit can be operated. Advantages in its manufacture 75 are the smallness of the labor cost in assembling the unit; the saving in work and in quantity of sealing alloy by not removing the central interior mound when the cap is made; the further saving of sealing alloy 80 by reason of the quasi-meniscus surface edges; and the saving of labor and the cost of plug and of glass breakage heretofore experienced. Another feature is the uniformity of product obtainable by the process, 85 as regards approximation of the unit to the standard value predetermined for it; and another the mechanical strength with which the sealing alloy, rising within the glass and forced up outside of it within the barrel of 90 the cap, holds the glass in the cap.

I claim as my invention:

1. A resistance unit comprising an insulating tube with interiorly coated resistance in tubular form; a terminal, fitting over an 100 end of the tube, with internal control mound; and a sealing medium connecting said mound to said interiorly coated resistance.

2. A resistance unit comprising an insulating tube with interiorly coated resistance; 105 a metallic cap with internal mound and with internal annular groove around the mound adapted to receive an end of said tube; and means within said groove connecting said cap electrically to said interiorly coated resist- 110 ance with incidental mechanical connection of it to the tube.

3. A resistance unit comprising an insulating tube with interiorly coated resistance; 115 a metallic cap into which an end of said tube is set; and an alloy within the cap, solidified with an annular concave surface extending between the interior surfaces of tube and cap, connecting the tube and cap mechanically and electrically.

4. A resistance unit comprising an insulating tube with interiorly coated resistance; 125 an interior terminal therefor, comprising a band coating the end of the inner surface of the tube, of greater conductivity than other portions of said inner surface; a metallic cap into which the end of said tube with band is set; and an alloy within the cap, solidified with a concave surface rising over the said 130

band, connecting the tube and cap mechanically and electrically.

5. A resistance unit comprising an insulating tube with interiorly coated resistance; a metallic terminal cap, with internal mound, for the end of the tube; and an alloy connecting said mound annularly with the interior of the tube mechanically and electrically, part of said alloy being within and adhering to the end portion of the tube; and the said alloy being of a variety whose melting point is of an order above that of the order of alloys comprising approximately half lead and half tin.
- 10 6. A resistance unit comprising an insulating tube with interiorly coated resistance; a metallic cap, with internal annular groove adapted to receive an end of said tube so that an annular wall of the cap is outside and a central mound of the cap is inside said tube; and an alloy solidified with a concave surface rising annularly over the inner surface of the tube, connecting the tube and cap mechanically and electrically.
- 15 7. A resistance unit comprising an insulating tube with interiorly coated resistance; metallic terminal caps for the ends of the tube, each cap having a portion enclosing and a portion enclosed by the end part of the tube; and a body of solid conducting material at the end part of the tube extending thence to said enclosing and enclosed parts of the cap, filling the annular space between cap and tube, and connecting the cap mechanically and electrically to the tube.
- 20 8. A resistance unit comprising an insulating tube with interiorly coated resistance, and a terminal cap fixedly connected therewith, having for exterior connection a portion which is fixed relative to the tube and is grooved transversely of the axis of said unit.
- 25 9. A resistance unit comprising an insulating tube with interiorly coated resistance having terminal caps, each with exterior portion grooved transversely of the axis of said unit for exterior connection, the grooves at the two ends being set at an angle with respect to each other about the axis.

Signed at Boston, Massachusetts, this fourteenth day of January, 1928.
